PRIMING MEANS FOR CENTRIFUGAL PUMPS

Alfred L. Grisé, Springfield, Mass., assignor to
 Gilbert & Barker Manufacturing Company,
 West Springfield, Mass., a corporation of
 Massachusetts

Application March 14, 1951, Serial No. 215,446

4 Claims. (Cl. 103—113)

1

This invention relates to improvements in priming means for centrifugal pumps.

It has been common heretofore to provide as a priming means for a centrifugal pump, such for example as a rotary pump of the type in which a rotor with radially movable vanes is mounted to rotate in, and on an axis eccentrically of a pump chamber. The priming pump needs to be large enough to speedily scavenge the suction pipe and impeller chamber. With a priming pump of this character, it is desirable to avoid needless work by the priming pump and the resulting loss of power and also wear on the parts after the priming operation has been accomplished. Prior art examples include a clutch, which uncouples the priming pump from its driving means, after priming has been effected; an unloading means for the priming pump, operable after priming has been effected to open a by-pass, which interconnects the suction and pressure sides of the priming pump; and a variable capacity priming pump with means for reducing its pumping rate after the centrifugal pump has been primed.

This invention provides an improved arrangement for the purpose and has for an object to utilize the priming pump as a fluid coupling between the drive shaft and the impeller of the centrifugal pump, after the latter has been primed.

More particularly, the invention has for an object the provision in a centrifugal pump of a priming pump having relatively rotatable elements one of which is fixed to the driving shaft and the other to the impeller of the centrifugal pump, with means for frictionally holding the impeller stationary until liquid fills the priming pump under sufficient pressure to substantially prevent relative movement between said elements.

These objects will best be understood from the following description of one illustrative example of the invention in the accompanying drawings, in which:

Fig. 1 is a sectional elevational view of a centrifugal pump embodying the invention;

Fig. 2 is an elevational view taken from the right of Fig. 1 and having parts broken away and in section to show the priming pump;

Fig. 3 is a fragmentary cross sectional view taken on the line 3—3 of Fig. 1 and showing the outlet port of the priming pump;

Fig. 4 is a fragmentary sectional plan view taken on the line 4—4 of Fig. 2; and

2

Fig. 5 is a fragmentary cross sectional view taken on the line 5—5 of Fig. 1.

Referring to these drawings; the centrifugal pump includes a main casing 1 (Fig. 1) and a cover section 2, suitably secured together, as by the cap screws 3, and affording between them a chamber 4 to receive the impeller 5. The casing is supported by a standard 6 to which it is suitably secured as by cap screws 7. The impeller 5, as herein shown, is of the closed type and has a circular series of vanes 8 and a central axially-directed eye 9 leading to the space between the vanes. Casing 1 has in its end wall a central opening 10, in axial alignment with the impeller and its eye 9, and in this wall and surrounding the inlet 10 are a series of tapped holes 11, which enable the flanged end of a suction pipe (not shown) to be clamped to the casing.

20 The casing 1 has formed therein the volute channel 12 (Fig. 2), surrounding the chamber 4 and the impeller 5 and terminating in an outlet 13. The latter has fixed therein a bushing 14, providing a seat for a check valve 15, which has 25 guide vanes 16 slidably engaging the inner peripheral wall of the bushing. A spring 17, acting between a cross bar 18, which is fixed at its ends to the casing 1 and diametrically spans the outlet passage 13, and the valve 16, holds the latter 30 to its seat until a sufficient pressure is built up in the centrifugal pump to open the valve.

The pump, as thus far described, is of old and well known form and it will serve as an illustrative example of one form of centrifugal pump, in which the priming means of this invention may be embodied. The invention may be used with any centrifugal pump and does not depend on, nor is it limited to, the particular details of construction disclosed.

35 The impeller 5 (Fig. 1), is supported on the inner end of a drive shaft 19 with freedom to turn and move axially thereon. This shaft is mounted in ball bearings 20 in a casing 21, the inner flanged end of which is suitably fixed, as indicated, to the outer end of a hollow hub 22 on cover 2. The bearings also hold the shaft 19 against axial movement. The opening in the inner end of casing 21 is closed by a cover 23 suitably fixed thereto, as indicated, and located 40 within the hollow hub 22. This cover 23 has a stuffing box 24, or other suitable means, for preventing leakage of liquid into the interior of bearing casing 21 and is also provided with a small annular bearing surface 25. The impeller 45 5 has a hollow cylindrical hub 26 rotatably

3

mounted in a sleeve 21 in the hub 22 of cover 2. The outer end of hollow hub 26 is closed (except for certain passages later to be described) by a cover 28, suitably fixed to the outer end face of the hollow hub, as indicated. This cover 28 has a small annular bearing surface 29 (Fig. 5) to engage the surface 25 on cover 23. A spring 30 (Fig. 1), coiled around the inner end of shaft 19, acts between a collar 31 on the shaft and the inner end face of the impeller 5 to press the bearing surface 29 against the surface 25 for the purpose of frictionally holding the impeller 5 stationary during the operation of the priming pump to be described.

The priming pump is of the positively-acting displacement type and is mounted within the hollow hub 22 of the impeller 5. As shown in Fig. 2, this hub has a cylindrical pump chamber 32, which is eccentrically disposed in the hub and receives a cylindrical rotor 33, fixed to shaft 19, as indicated. Rotor 33 is radially grooved at angularly spaced intervals to slidably receive blades 34, which are held with their outer edges pressed against the peripheral wall of chamber 32 by means of two annular rings 35, mounted one in each of two recesses formed in opposite ends of the rotor. In the inner end wall of the pump chamber 32 is an arcuate recess 36, forming the inlet port of the priming pump, and this recess is connected by a series of holes 37 with the inlet eye 9 of the impeller. The outlet port (Fig. 3) consists of an arcuate groove 38 in the inner face of the cover 28 and this groove is connected by one or more holes 39 to the space within the hub 22 and between the covers 23 and 28. This space is connected by a conduit 40 to the outlet 13 of the centrifugal pump at a point above the check valve 15.

The holes 39 provide a restricted outlet for the priming pump. They provide in the aggregate sufficient cross sectional area so as to freely pass all the air or gas that the priming pump can pump but not enough area to pass all the liquid that the pump can pump.

In operation, when power is initially applied to shaft 19, the rotor 33 will turn but because the spring 39 presses the bearing face 29 against the bearing face 25, the impeller 5 will be frictionally held against rotation as will also the stator of the priming pump, which is the hub of the impeller. The priming pump draws air and/or gases from the suction pipe and chamber 4 through the openings 37 in the impeller 5 into the inlet port 36 and expels such air and/or gases through the outlet port 38, holes 39, into the space within hub 22 and between the covers 23 and 28 and thence through conduit 40 to the outlet 43 above check valve 45. The holes 39 will pass all the air or gases that can be pumped but they restrict the flow of liquid. Hence, when the centrifugal pump is primed and liquid enters and fills the pump chamber 32, the liquid cannot escape as fast as it is pumped in and pressure builds up within this chamber which pressure soon is sufficient to bind the hub of the impeller to the rotor of the priming pump and cause rotation of the impeller. The priming pump serves like a fluid clutch or coupling to drive the impeller from the rotor of the priming pump after the centrifugal pump has been fully primed.

Thus, the invention provides a fluid drive from the rotor of the priming pump to the impeller of the centrifugal pump, whereby after the priming operation has been effected, relative

movement between the rotor and stator of the priming pump is avoided, or substantially reduced, to avoid wear on the blades of the priming pump. The arrangement renders unnecessary the use of a by-pass to unload the priming pump or a clutch to stop the latter after the priming operation has been accomplished, as has heretofore been deemed necessary in centrifugal pumps of the class described in order to avoid needless work and loss of power or to avoid wear between the engaged parts of the rotor and the stator of the priming pump.

What is claimed is:

What is claimed is:

1. The combination with a centrifugal pump, having a casing provided with a chamber, having an inlet and an outlet and having an impeller mounted to rotate in such chamber, of a priming pump of the positively-acting displacement type comprising a casing element affording within it a pump chamber with an inlet connected to and in unrestricted communication with the first-named inlet and chamber and an outlet, and a piston element mounted in said second chamber for rotation relatively thereto and operable on such relative rotation to draw in fluid from the first to the second inlet and force it through the second chamber to the second outlet, one of said elements being fixed to said impeller, a drive shaft fixed to the other of said elements and passing through the impeller and free to turn relatively thereto, said second-named outlet provided with a restricted portion of an area such as to freely pass all the air and gases that the priming pump piston can draw into and force through the second-named chamber but not all the liquid that such pump piston can draw into the second-named chamber, and means for frictionally holding the impeller to its casing to hold the impeller and one of the priming pump elements against rotation during the priming operation, the priming pump chamber when filled with liquid under pressure acting as a fluid clutch to drive the impeller from the driven element of the priming pump.

45 2. The combination with a centrifugal pump, having a casing provided with a chamber, having an inlet and outlet and having an impeller mounted to rotate in such chamber; of a priming pump of the positively-acting displacement type
50 comprising a stator fixed to the impeller and provided with a chamber having an inlet extending through the impeller and connected to and communicating with said first-named inlet and an outlet having a portion of restricted area, a piston 55 rotatably mounted in the second-named chamber for drawing fluid from said inlets into and forcing it through the second-named chamber to the outlet of the latter, a drive shaft fixed to said piston and passing through the impeller and free to turn relatively thereto; means for 60 frictionally holding the impeller to its casing against rotation, said portion of restricted area freely passing all the air or gases that the priming pump piston can draw into the second-named chamber but not all the liquid that the pump 65 piston can draw into the second-named chamber, whereby after the centrifugal pump has been primed the chamber in the stator becomes filled with liquid under pressure and causes the impeller 70 to be driven from the piston.

3. The combination in a centrifugal pump having a casing provided with a chamber having a central inlet and a peripheral outlet and an impeller having on one side an inlet communicating with the first-named inlet and on the op-

posite side a hub provided with a cylindrical priming pump chamber the axis of which is eccentric to the axis of the impeller, a rotor in the last-named chamber coaxial with the impeller and having piston blades engaging the walls of the priming pump chamber, a drive shaft fixed to the rotor and passing through the impeller and free to turn relatively thereto, said priming pump chamber having an inlet port connected to and communicating through the impeller with both said inlets and an outlet port, a conduit connecting said outlet port to the first-named outlet and having a restricted portion of an area such as to freely pass all the air and gases that the priming pump piston blades can draw into the priming pump chamber but not all the liquid that such pump piston blades can draw into the priming pump chamber, and means for frictionally holding the impeller to its casing to hold the impeller and the hub containing the priming pump chamber against rotation during the priming operation, the priming pump chamber when filled with liquid under pressure acting as a fluid clutch to drive the impeller from the driven rotor of the priming pump.

4. The combination in a centrifugal pump, having a casing provided with a chamber having a central inlet and a peripheral outlet and an impeller having on one side an inlet communicating with the first-named inlet and on the opposite side a hub provided with a cylindrical priming pump chamber the axis of which is eccentric to the axis of the impeller, a rotor in the last-named chamber coaxial with the impeller and having piston blades engaging the walls of the priming pump chamber, a drive shaft fixed

to the rotor and passing through the impeller and free to turn relatively thereto, a collar fixed to the inner end of said shaft, a spring acting between said collar and impeller to move the latter axially and press a portion of its hub against the casing to frictionally hold the impeller against rotation, said priming pump chamber having an inlet passage connected to and communicating through the impeller with both said inlets and an outlet port, a conduit connecting said outlet port to the first-named outlet and having a restricted portion of an area such as to freely pass all the air and gases that the priming pump piston blades can draw into the priming pump chamber but not all the liquid that such pump piston blades can draw into the priming pump chamber, said means for frictionally holding the impeller to its casing holding the hub containing the priming pump chamber against rotation during the priming operation, the priming pump chamber when filled with liquid under pressure acting as a fluid clutch to drive the impeller from the driven rotor of the priming pump.
